FURNITURE PANEL OR THE LIKE

Richard M. Chapin, Charlotte, N.C., assignor to C. B. Atkin Company, Knoxville, Tenn., a corporation of Tennessee

Filed Oct. 14, 1968, Ser. No. 13,957

Term of patent 3½ years

Int. Cl. D6—01

U.S. Cl. D33—1

FIG. 1 is a front elevational view of a furniture panel showing my new design;

FIG. 2 is a left side elevational view of the furniture panel shown in FIG. 1;

FIG. 3 is a top plan view on an enlarged scale of the furniture panel shown in FIG. 1;

FIG. 4 is a horizontal sectional view on an enlarged scale taken along line 4—4 in FIG. 1; and

FIG. 5 is a vertical sectional view on an enlarged scale taken along line 5—5 in FIG. 1.

The back of the furniture panel shown is substantially plain and unornamented.

I claim:

The ornamental design for a furniture panel or the like, substantially as shown and described.
